Patented Mar. 10, 1925.

UNITED STATES PATENT OFFICE.

ABRAHAM M. ZIMMERMAN, OF LANCASTER, PENNSYLVANIA.

GRINDING MILL.

Application filed September 10, 1923. Serial No. 662,018.

To all whom it may concern:

Be it known that I, ABRAHAM M. ZIMMERMAN, a citizen of the United States, and resident of Lancaster, in the county of Lancaster and State of Pennsylvania, have invented certain new and useful Improvements in Grinding Mills; and I do hereby declare the following to be a full, clear, and exact description of the invention, such 10 as will enable others skilled in the art to which it appertains to make and use the same.

This invention relates to improvements in grinding mills such as may be employed for grinding feed, the invention being more particularly directed to an improved hopper construction.

One object of my present invention is to so construct the hopper of a grinding mill 20 that bridging of material, such as unshelled corn, over the crushing devices shall be prevented.

A further object is to provide a hopper construction whereby the weight of the 25 material under treatment shall be reduced to a minimum over the crushing devices.

A further object is to provide, in a hopper structure for a grinding mill, simple and efficient means to prevent material 30 from being thrown out of the hopper by the rapidly rotating crushing devices.

A further object is to provide means in a hopper structure, which may be employed to prevent the too rapid feeding of grain, such as shelled corn, to the grinding 35 devices and thus avoid clogging and undue work and strain on the mechanism as well as on the driving means.

With these and other objects in view, the 40 invention consists in certain novel features of construction and combinations of parts as hereinafter set forth and pointed out in the claims.

In the accompanying drawings,—

45 Figure 1 is a plan view of a mill structure showing an embodiment of my invention.

Figure 2 is a longitudinal sectional view, and

50 Figure 3 is a sectional view illustrating the position of the cover member 12 when employed to prevent clogging of shelled corn.

The base frame of the mill is represented 55 at 1 and supports a hopper 2. This hopper is elongated in form, having a long,

gradually sloping bottom 3 and an inclined end member 4 which is disposed at approximately right angles to the sloping bottom 3 and at the juncture of the members 3 and 4 of the hopper, a concave 5 is formed. The opposite or higher end of the hopper may be closed as at 6, or, if desired the closure at this end of the hopper may be omitted and a trough extension 7 60 65 provided.

Over the concave portion 5, a shaft 8 is mounted in suitable bearings so as to be disposed transversely of the hopper and carries a plurality of spirally-arranged 70 crushing lugs or fingers 9 which serve to crush ears of corn, for example, and to also feed the crushed material to grinding plates illustrated at 10 at one side of the hopper, and suitable means may be provided for 75 regulating one of said plates relatively to the other but as these devices per se constitute no part of my present invention, they need not be further described herein. The shaft 8 projects beyond its bearings 80 at one end and is provided with a pulley 11 to receive a strap from any suitable source of power.

A cover member 12 is hinged, as at 13, 85 at the upper end of the end wall 4 of the hopper and is disposed over that portion of the latter over the crushing devices. A plate or latch 14 is pivotally connected with the cover 12 and rests upon a transverse rod or bar 15 for supporting said cover 90 member over a portion of the top of the hopper.

The rod or bar 15 has its ends fitted in the side walls of the hopper and also serves to provide a support for a curtain 16 which is suspended therefrom so as to depend within the hopper in position to prevent corn and cob particles from being thrown out of the hopper beyond the cover member by the rapidly rotating crushing devices and the cover member 12 prevents the material being treated from being thrown upwardly out of the hopper. 95 100

By constructing the hopper elongated in form and having a gradually sloping bottom, near the lower end of which the crushing devices are located, the ears of corn will slide downwardly over said bottom and will be met by the crushing devices and the corn will be prevented from so accumulating directly over the crushing devices as to cause sufficient weight to enable ears of corn 105 110

to become so disposed over the crushing devices as to bridge the latter and prevent said crushing devices from reaching the corn. The cover 12 will also tend to prevent such weighty accumulation of corn over the crushing devices.

When the mill is used for grinding shelled corn, it is very desirable that a considerable weight of the grain over the crushing and feeding devices shall not be permitted as such crushing and feeding devices would feed the grain too rapidly to the grinding plates or disks and result in clogging and in putting over work upon the same and upon the driving mechanism and may result in stopping the operation of the mill. To prevent such conditions, I utilize the hinged cover member to prevent the accumulation of a large amount of grain directly over the crushing and feeding devices. When the cover member 12 is thus utilized, it is caused to depend in an inclined position over the crushing and feeding devices and supported in such position by lugs or pins 16 projecting inwardly from the sides of the hopper. Such position of the cover member is illustrated in Figure 3 and when disposed in the position here shown, a considerable amount of grain may be permitted to accumulate in the body portion of the hopper, as illustrated by the lines 17 and 18 but its entrance to the space over the crushing and feeding devices will be restricted by the inclined cover member 12 and only such amount be allowed within the chamber formed by the end wall 4 and the cover member 12 to enable the normal feeding of the grain to the grinding mechanism without subjecting the parts to strain and to avoid clogging. The amount of grain normally in said chamber may be such as indicated by the dotted line 19 in Figure 3.

Having fully described my invention what I claim as new and desire to secure by Letters Patent, is:

1. In a grinding mill of the character described, the combination of an elongated hopper having an inclined bottom, an end wall at approximately a right angle to the bottom at the lower end thereof, and a concave uniting the bottom and the end wall in a continuous imperforate structure, and

crushing and feeding means located in proximity to the concave.

2. In a grinding mill of the character described, the combination of an elongated hopper having an imperforate inclined bottom merging at its lower end into an imperforate end wall, the latter being disposed at approximately right angles to said bottom, and crushing and feeding means within the hopper in proximity to the bottom and the end wall.

3. In a grinding mill of the character described, the combination of a hopper, a feeding and crushing member in the hopper adjacent the end wall thereof, a cover hinged to the end wall and extending forwardly therefrom over the feeding and crushing member, and means whereby the cover may be supported at the top of the hopper or in a lowered position extending across the feeding and crushing member.

4. In a grinding mill of the character described, the combination of a hopper, a crushing and feeding member therein, an adjustable cover above the crushing and feeding member, and a freely swinging curtain in advance of the crushing and feeding member.

5. A grinding mill comprising an elongated hopper having a bottom and an end wall, crushing and feeding means arranged within the hopper at the juncture of the bottom and the end wall, a rod extending across the hopper above and in advance of the said means, a curtain depending from said rod, studs on sides of the hopper adjacent the crushing and feeding means, a cover member hinged to the upper end of the end wall and adapted to extend downwardly and forwardly therefrom to rest on said studs, and a latch on the cover member adapted to engage said bar and support the cover member in a position extending along the top of the hopper.

In testimony whereof I have signed this specification in the presence of two subscribing witnesses.

ABRAHAM M. ZIMMERMAN.
